HAIR CURLING DEVICE

Rocco Pezzella, Washington, D. C.

Application January 16, 1934, Serial No. 706,867

13 Claims. (Cl. 132—33)

The present invention relates to mandrels used in the production of permanent waves in the hair.

In the mandrels for waving hair that are now in common use, the means provided for clamping the lock of hair to be wound is commonly located at one end of the mandrel extending outwardly therefrom. Consequently the surface upon which the hair is wound is more or less uneven, instead of being wholly smooth and free from obstruction 10 as is desirable for the smooth and even wrapping necessary for good results.

The object of the invention is to provide a mandrel having a smooth cylindrical surface upon which the hair is to be wound, and means 15 entirely within the surface of the mandrel for clamping a lock of hair to be wound upon the mandrel.

Another object is to provide in such a mandrel easily operated means for quickly and effectively 20 clamping a lock of hair.

In the accompanying drawing:

Figure 1 is a perspective view of the device having a lock of hair wound thereon.

Figure 2 is a longitudinal sectional view of the 25 device.

Figure 3 is a view taken on line 3—3 of Figure 2 and in the direction of the arrow.

Figure 4 is a sectional view similar to Figure 3 of the core member only.

Figure 5 is a sectional view on line 5—5 of 30 Figure 2 looking in the direction of the arrow.

Figure 6 is a sectional view similar to Figure 3, showing a lock of hair wound upon the mandrel and the parts in clamping position.

Figure 7 is a perspective view of the sheath 35 member.

Figure 8 is a perspective view of the core member.

Figure 9 is a perspective view of the plunger 40 which prevents relative rotation of the core and sheath from the reaction of the hair wound thereon.

Describing the preferred embodiment shown in the accompanying drawing, the numeral 10 designates generally a cylindrical core having at one 45 end an enlarged head 11. Cut in the inner face of this head is a circular channel 12, the inner circumference of which is equal to the circumference of the core 11.

At a point slightly spaced from the inner face of the head 11, the core 10 is cut away to form a reduced portion 13 longitudinally eccentric to the core 10 and having an outer transversely disposed cam surface 14 which approaches the plane 50 of the surface of the core 10. It is to be noted

that this cam surface 14 does not at any point extend beyond the surface of the core 10, and that it is longitudinally flat.

Surrounding the core 10 and rotatably mounted thereon is a tubular sheath upon which the 5 hair is intended to be wound. This sheath may be made in sections 15 and 16.

The section 15 is positioned adjacent the head 11 and its end is engaged in the slot 12. The end of the member 15 which abuts the head of the core has diametrically opposite slots 17, the edges of which are designated 18. The slots 17 extend longitudinally a distance at least as great as the cutaway portion of the core.

The member 16 abuts the member 15 and extends longitudinally a short distance beyond the end of the core member 10, where it carries a screw 19, having threads that are preferably sharply pitched for quick action, this screw engaging in a threaded socket in the adjacent end 20 of the core.

In order to prevent the sheath 16 from turning due to the reaction of hair wound thereon, to-wit, its tendency to unwind, and thus allowing the hair to become loose about the device, a special 25 type of spring-pressed plunger is employed. The plunger designated 20 and its backing spring, is received in a square socket in the core member 10. The plunger consists of a square base 21, which keeps it from turning, and has a stud 30 22 projecting therefrom. The stud 22 is of no greater height than the thickness of the wall of the sheath 16.

The stud 22 has one flat surface or face and the rest of its surface is rounded off.

Properly positioned to receive the stud 22 of the plunger is a series of holes 23 in the sheath 16. It will be understood from consideration of Figure 9, that due to the flat face and rounded surface of the stud the core may be moved relatively to 40 the sheath 16 in any direction except that in which the flat face is positioned. In use this face is turned in the direction opposite to that in which the hair is wound, thus holding the sheath against rotation in a direction to permit the tendency of the hair to uncoil to cause the sheath to rotate upon the core. Due to the rounded surface the sheath may, however, be pulled longitudinally from the core, or turned in the direction to tighten the hair thereon.

When the device is to be used, the screw 19 is loosened and the sheath sections are pulled away from the head 11 to expose the reduced portion 13 of the core. The portion of the lock of hair near the head is then placed over this portion, 55

and the sheath member 15 turned so that the lock of hair passes through the slots 17, when the member is returned to its position with its end engaged in the channel 12. The core 10 and the member 15 are then relatively rotated in the proper direction, with respect to the cam face 14, to cause the cam face to approach one of the edges 18 of one of the slots, thus securely clamping the lock of hair. The sheath member 16 now 10 may be placed adjacent the member 15 with the stud 22 of the plunger engaged in one of the holes 23, and secured by tightening the screw 19, thus clamping the sheath 15 against the head 11. It will be noted that instead of bunching the hair 15 the clamp acts to flatten the lock. After this the operator winds the hair upon the surfaces of the sheath sections 15 and 16 and secures it by any suitable means, not here shown.

The advantages of this device are that it presents a smooth hair supporting surface, unbroken by anything which might cause the forming of kinks in the hair being treated. Further, it provides simple and easily operated means for securely clamping the hair without cutting or 20 breaking it, and without causing any sharp bend therein to spoil the effect of the wave, and also means to prevent the parts from slipping due to the tendency of the wound hair to unwind. The device is easily manufactured and of few 30 parts, hence may be made very inexpensively.

From the foregoing, it is thought that the construction, operation and many advantages of the herein described invention will be apparent to those skilled in the art without further description, and it will be understood that various 35 changes in the size, shape, proportion and minor details of construction may be resorted to without departing from the spirit or sacrificing any of the advantages of the invention.

40 What I claim, is:

1. A hair curling mandrel comprising a tubular sheath having a slot therein, a cam positioned wholly within the sheath adjacent the slot and rotatable with relation thereto and cooperating 45 with the edge of the slot in the sheath to form hair clamping means.

2. A hair curling mandrel comprising a sheath having a longitudinal edge, a core rotatable within the said longitudinal edge of the sheath, and a cam rotatable with the core and cooperating 50 with the sheath to form hair clamping means.

3. A hair curling mandrel comprising a tubular sheath having a slot therein, a core within the sheath, and a rotatable cam eccentric to the core 55 and lying wholly within the circumference thereof, the said cam cooperating with the edge of the slot in the sheath to form means for clamping a lock of hair passing through the slot.

4. A hair curling mandrel comprising a tubular 60 sheath having diametrically opposite slots therein at one end, a core rotatably positioned within the sheath and having a head adapted to act as a stop for the slotted end of the sheath, eccentric clamping means wholly within the sheath and 65 rotatable with the core, the said clamping means being positioned adjacent the head of the core to cooperate with the slots for clamping hair passing through the slots, and means at the opposite end of the core for tightening the sheath

against the head of the core to prevent relative rotation of the sheath and core.

5. A hair curling mandrel comprising a cylindrical core having a head at one end thereof, and a cam portion adjacent the head and lying wholly 5 within the diameter of the core, a tubular sheath of less length than the core rotatably surrounding the core and having a portion adjacent the head thereof provided with diametrically opposite slots for the reception of a lock of hair and adapted to 10 cooperate with the cam portion to clamp a lock of hair passed through the slots, a second tubular sheath mounted upon the core and abutting the first sheath, means for allowing the second sheath to be rotated in one direction only, and means 15 for clamping both of the sheaths against rotation relative to the core.

6. A hair curling mandrel comprising a cylindrical core, a tubular sheath mounted upon the core and upon which hair is wrapped, the said 20 sheath and core having clamping means for the hair wrapped thereon, said clamping means cooperating on the relative rotation of the core and sheath.

7. A hair curling mandrel comprising a cylindrical core, a sheath rotatably mounted upon the core and upon which hair is wrapped, parts of 25 said core and of the said sheath constituting clamping means for the hair wrapped thereon, said clamping means cooperating on the relative rotation of the core and sheath.

8. A hair curling mandrel comprising a cylindrical core, clamping means on the core in the rear of the terminal thereof, a sheath mounted thereon and upon which hair is wrapped, the 30 said sheath having means for cooperating with the clamping means on the core for clamping the hair wrapped thereon.

9. A hair curling mandrel comprising a cylindrical core having a reduced portion, the face of 40 which is eccentric therewith, and a sheath surrounding the reduced portion and having a slot therein, the edge of the slot cooperating with the eccentric face to form means for clamping hair.

10. In a hair curling device a clamp for holding 45 hair comprising a cam and a sheath surrounding the cam and having a slot therein, said cam and slot having parallel longitudinally flat edges between which the hair is clamped.

11. In a hair curling mandrel a core having an 50 enlarged head at an end thereof, the said head having a circular groove therein adapted to receive the end of a sheath surrounding the core.

12. A hair curling mandrel comprising a core, a relatively movable sheath surrounding the core 55 and having a recess therein, and a ratchet carried by the core and engaging the recess to prevent the sheath from turning in one direction relative to the core.

13. A hair curling mandrel comprising a core, 60 a relatively rotatable sheath surrounding the core and having a recess therein, and a ratchet carried by the core and engaging the recess to prevent the sheath from turning in one direction relative to the core, said ratchet holding the sheath against 65 rotation on the core in one direction and permitting its rotation in the opposite direction and its longitudinal movements on the core.

ROCCO PEZZELLA.
